US00D523179S

(12) **United States Design Patent** (10) **Patent No.:** **US D523,179 S**
Py et al. (45) **Date of Patent:** **** Jun. 13, 2006**

(54) **COSMETIC APPLICATOR**

(75) Inventors: **Daniel Py**, Stamford, CT (US); **Julian V. Chan**, Spring Valley, NY (US); **Stephanie Ferreira**, Bridgeport, CT (US); **Gladys Valencia**, Stamford, CT (US)

(73) Assignee: **Medical Instill Technologies, Inc.**, New Milford, CT (US)

(**) Term: **14 Years**

(21) Appl. No.: **29/227,060**

(22) Filed: **Apr. 6, 2005**

Primary Examiner—Jennifer Rivard

(74) *Attorney, Agent, or Firm*—McCarter & English, LLP

(57) **CLAIM**

The ornamental design for the cosmetic applicator, as shown and described.

DESCRIPTION

FIG. 1 is back side elevational view of our new cosmetic applicator design;

FIG. 2 is a left side elevational view of the cosmetic applicator of FIG. 1;

FIG. 3 is a top and front side perspective view of the cosmetic applicator of FIG. 1;

FIG. 4 is a bottom and back side perspective view of the cosmetic applicator of FIG. 1;

FIG. 5 is a front side elevational view of the cosmetic applicator of FIG. 1;

FIG. 6 is a top plan view of the cosmetic applicator of FIG. 1; and,

FIG. 7 is a bottom plan view of the cosmetic applicator of FIG. 1.

The broken lines immediately adjacent the shaded areas represent the bounds of the claim and all other broken lines are for illustrative purposes only. None of the broken lines form a part of the claimed design.

1 Claim, 7 Drawing Sheets
